[57] CLAIM

The ornamental design for an electric lamp lens, as shown and described.

DESCRIPTION

FIG. 1 is a front view of an electric lamp lens illustrating my new design;

FIG. 2 is a rear elevational view thereof; and,

FIG. 3 is side elevational view thereof, all sides being equivalent.

The lamp is rotationally symmetric, so the top, right side, left side and bottom views are equivalent. The lens material is clear glass with plano-convex lenticules formed on the rear side. The curvatures of each lenticule is not specifically shown.
